UNITED STATES PATENT OFFICE.

ARTHUR L. HALLIDAY, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 14,021, dated July 3, 1883.

Application filed March 16, 1883. Term of patent 3½ years.

To all whom it may concern:

Be it known that I, ARTHUR L. HALLIDAY, of New York, in the county and State of New York, have invented a new and original Design 5 for Carpets, of which the following is a specification.

The accompanying photograph illustrates a face view of my new design for carpet.

This invention relates to a new design for 10 carpet and analogous fabrics; and it consists of the new configuration of groups and figures that make up the groundwork of the carpet.

The design is made up of a series of squares set alongside one another, like the squares on 15 a checker-board. The square D contains an ornamentation resembling an octagon, which contains within it a leafy branch. The square E is ornamented with a branch bearing circular figures. The square h contains a leaf. i 20 contains a Maltese cross with a flower in its center; l, a dotted figure of square form with cut-away corners; m, three-pointed leaves. o contains a leafy branch; q, a leaf-like figure; r, a figure resembling a Maltese cross, with ornamentation in the center; F, a flower-like figure; s, a figure resembling a leaf with several branches; d, a figure resembling a Maltese cross; f, a leaf-like figure; t, a Maltese cross with ornamentation in the center; u, a dotted

figure, and e a flower-like figure. Other 30 squares, a, b, c, g, n, p, j, and v, complete the design, each having its own characteristic ornamentation.

I claim—

1. The design for carpets, consisting of the 35 figure D, substantially as shown.
2. The design for carpets, consisting of the figure E, substantially as shown.
3. The design for carpets, consisting of the figure l, substantially as shown. 40
